UNITED STATES PATENT OFFICE

1,931,410

LAUNDRY MACHINE

Otis H. Hullings, Alexandria, Va.

Application February 9, 1933. Serial No. 655,983

1 Claim. (Cl. 68—18)

This invention relates to improvements in laundry machines generally, and more particularly to washing machines to be employed in laundries of large capacity.

5 This application is a continuation in part of an application for Letters Patent of the United States on improvements in Laundry machines, which was filed by me on March 14, 1928 (Serial No. 261,468).

10 An object of the invention is to provide a washing machine with a water inlet and an outlet drain whereby it will function to wash and rinse articles to be laundered in a substantially continuance operation.

15 Another object of the invention is to eliminate, in carrying out the aforesaid continuance washing and rinsing operation, the settling of soil laden froth of a used washing solution on the previously washed batches of articles, such as 20 would occur in the old method of operation of washing machines wherein the used washing solution is discharged from a machine prior to subjecting the washed articles to rinsing water, which elimination is accomplished in a manner 25 that the used solution is gradually forced out of the machine and from the washed articles by admitting rinsing water to the machine immediately following the completion of a washing operation, thus leaving the washed articles in a 30 semi-rinsed and much cleaner condition than would otherwise be the case and ready for the succeeding rinsing operation upon the complete evacuation of the used washing solution from the machine.

35 A further object of the invention resides in the provision of an adjustable drain device and an associated indicator, in the operation of which the drain may be set to maintain a desired depth of washing solution or rinsing water in the machine during a washing and rinsing operation and thereafter positioned to completely evacuate the used liquid content from the machine following the final rinsing operation.

With the foregoing and other equally important objects and advantages in view, the invention resides in the certain new and useful combination, construction and arrangement of parts as will be hereinafter more fully described, set forth in the appended claim, and illustrated in 50 the accompanying drawing in which:

Figure 1 is a side elevation of the improved laundry machine, and

Figure 2 is an end elevation thereof.

Referring to the drawing, wherein like characters of reference designate corresponding parts

in the two views thereof, the embodiment of the invention, as exemplified therein, is comprised in a washer body 10 which is preferably of horizontal cylindrical form to house a wash carrier or drum (not shown) mounted on a driven shaft 60 11. Access to the interior of the body 10 is had through an opening in its upper and forward side; the opening being normally closed by a movable cover 12.

A sediment trough 13 is provided at the bottom 65 side of the body 10 for the draining therefrom of a content of the body as required. A valved liquid inlet 14 opens inwardly of the rear wall of the body 10 at a point in the plane of or slightly below the lower edge of the opening at the forward side thereof.

In adapting the washing machine, as thus constructed and arranged, for the desired continuous washing and rinsing operation, one or more outlets 15 is provided in a side wall of the trough 75 13, and each outlet has a packing joint 16 on its free end for the coupling thereto of a vertically adjustable drain pipe or spout 17. Each pipe or spout 17 is preferably disposed in right angular relation to its coupled end for swinging 80 movement from a horizontal position to a vertical position of operation and has its free end of angled formation, as at 18, to discharge a liquid content of the body 10 to one side thereof.

Thus, when one or both of the drain pipes or 85 spouts 17 are disposed in their horizontal positions, which will place the discharge ends thereof below the level of the bottom wall of the trough 13, the liquid content of the body 10 will be completely drained therefrom, while, when swung in 90 an upward direction to any desired set angle of inclination, or to full vertical position, the liquid content of the body will be maintained at a selected depth therein.

In any case, the length of the pipes or spouts 95 17 is such that, when they are vertically disposed, the level of a liquid content of the body 10 will be immediately below the lower edge of the opening through which access is had to the interior of the body.

100 By this arrangement, no cutoff means need be provided to control the discharge of a liquid content from the body 10, since the required amount of the liquid will remain in the body at the set position of the pipes or spouts 17 during either 105 of the washing or rinsing operations, and the discharge of a used washing solution is readily accomplished by merely admitting rinsing water at the inlet 14, without disturbing the previously set positions of the pipes or spouts, at least at 110

the beginning of a rinsing operation. However, at the conclusion of a completed rinsing operation, the pipes or spouts 17 will be moved to horizontal position for the draining of the liquid content of the body 10, preparatory to the removal of the washed and rinsed articles and the commencing of the next washing operation.

In order to facilitate the operation of a drain pipe or spout 17, from a remote point but convenient to the operator of a washing machine of large capacity, a depth indicating quadrant 19 will be positioned toward one end of the machine body for the cooperation therewith of a hand lever 20 which is supported for swinging movements relatively thereto on a fixed pivot 21. The end of the lever 20, below its pivot 21, is pivoted, as at 22, to one end of a pitman 23, which has its other end pivoted in turn, as at 24, to an intermediate portion of a pipe or spout 17.

Thus, with the upper part of the lever 20 registered with the zero graduation on the quadrant 19, the connected pipe or spout 17 will be horizontally disposed for draining purposes, and, when the lever is swung to the opposite end of the quadrant, the pipe or spout will be elevated to vertical position for retaining a maximum depth of liquid in the body 10. By moving the lever 20 to the different graduations on the quadrant 19 between zero and maximum, the angle of inclination of the pipe or spout 17 will be correspondingly varied and any selected depth of liquid maintained in the washer body.

When more than one of the pipes or spouts 17 are employed, the pivot of the one nearest the lever 21 will be interconnected with a similar pivot 24 on the other thereof through a link 25, substantially as shown.

In the operation of a washer equipped with these drain pipes or spouts 17, and with the same disposed in vertical position, a wash solution, or water to be later saponified, will be admitted to the body 10 at the inlet 14 and until there is a flow from the pipes or spouts to indicate that the selected depth of liquid has been reached. If fresh water only is admitted at the inlet 14, then a detergent can be introduced thereto through the opening at the upper forward side of the body. With a proper wash solution in place, the articles to be washed will then be positioned on the carrier or drum, and the washer will be ready for the washing operation, which will be effected by imparting motion to the shaft 11.

Upon the completion of a washing operation, and without opening up the body 10, the inlet 14 will be opened to admit a supply of rinsing water which will displace the used washing solution and cause it to be evacuated from the pipes or spouts 17, the latter being allowed to remain in their previously set positions.

When the body 10 has been completely evacuated of the used washing solution, that fact will be indicated by the outflow of clear rinsing water from the pipes or spouts 17.

Now, after letting clear water flow through the body 10, during the continued rotation of the carrier or drum with the shaft 11, to effect a final rinsing of the previously washed articles, the pipes or spouts 17 will be returned to horizontal position for the complete draining of the liquid content from the body; the inlet 14 being preferably closed only when it is assured that all sediment has been washed out of the trough 13. When this assurance is had, the machine is in readiness for a repeat washing operation upon the removal of the previously washed and rinsed articles from the carrier or drum.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

I claim:

In a laundry machine, an elongated hollow body having a valved inlet toward its top side, spaced drain pipes extending laterally from beneath one side of said body, an overflow arranged for vertical angular adjustments on the free end of each drain pipe and acting to maintain a maximum depth of liquid within said body when adjusted to vertical position and to completely drain the body when horizontally disposed, a hand lever pivotally mounted at one end of said body, link connections between said overflows and said hand lever, and a graduated indicating means over which said lever is moved to allow for the setting of the lever and said overflows to selected positions of operation between the extremes of range in adjustment thereof.

OTIS H. HULLINGS.
